UNITED STATES PATENT OFFICE.

CHARLES A. CUNNINGHAM, OF ALVARADO, ANDREW CHRISTENSEN, OF ALAMEDA, AND FRANK W. BARTLETT, OF BERKELEY, CALIFORNIA, ASSIGNEES TO CONTINENTAL SALT AND CHEMICAL COMPANY, OF SAN FRANCISCO, CALIFORNIA, A CORPORATION OF CALIFORNIA.

SALT HARVESTER.

1,407,189.

Specification of Letters Patent. Patented Feb. 21, 1922.

Application filed September 20, 1919. Serial No. 325,263.

To all whom it may concern:

Be it known that we, CHARLES A. CUNNINGHAM, ANDREW CHRISTENSEN, and FRANK W. BARTLETT, citizens of the United States, 5 residing the said CUNNINGHAM at Alvarado, the said CHRISTENSEN at Alameda, and the said BARTLETT at Berkeley, all of Alameda County, State of California, have invented certain new and useful Improvements in 10 Salt Harvesters, of which the following is a specification.

Our invention relates to a harvester, especially adapted to travel over the beds of salt-ponds, and to penetrate, loosen, excavate, lift and dispose of the salt therefrom. 15

The objects of our invention are to provide a machine capable of propelling itself over the beds of salt-ponds, loosening and picking up the salt as it travels, and dumping 20 the same into suitable vehicles or other means of conveyance; and further to provide, in such a machine, both the necessary weight to insure proper excavation of the salt, and the requisite traction necessary 25 to enable the machine to travel over the more or less wet salt beds without sinking in.

These and other objects will be more fully elaborated with reference to the accompanying 30 drawings, wherein—

Fig. 1 is a plan view of our complete salt-harvester.

Fig. 2 is a side elevation of the same.

Fig. 3 is a vertical section taken in the 35 direction of the arrows on the line 3—3 of Fig. 1.

Fig. 4 is a vertical sectional detail, enlarged, of the pick-roll and conveyer foot, taken in the direction of the arrows on the 40 line 4—4 of Fig. 1.

Fig. 5 is a vertical sectional detail of the conveyer chain, taken on the line 5—5 of Fig. 4.

Fig. 6 is a longitudinal vertical section 45 through one of the shaft joints showing the shaft in elevation.

Referring in more detail to the drawings, the reference numeral 1 designates a frame, which is carried, by means of sprocket 50 wheels 2 and 3, upon a pair of endless track chains 4, Figs. 1 and 2. These track chains may be constructed in any well-known man-

ner, and are preferably shod with wooden tread blocks 5, to permit the employment of a comparatively wide and light track chain, capable of properly supporting the machine upon the soft bed of the salt pond. A sled 6, Fig. 2, operating on the upper surface of the lower run of the track chain 4, supports the frame 1 between the wheels 2 and 3. 55

The frame 1 carries, near its forward end, an engine 7, Figs. 1 and 2, here shown as an internal combustion engine having a fuel tank 8, Fig. 1, a cooling-water tank 9, and a cooler or radiator 10. Power from said engine 7 is transmitted through a pair of spur gears 11, a longitudinal shaft 12, and a friction bevel reversing mechanism 13, to a transverse shaft 14; thence through a pair of spur gears 15, a second transverse shaft 16, a set of selective sliding gears 17, a third transverse shaft 18, and a pair of spur gears 19, to a transverse pinion shaft 20, Figs. 1 and 2. Said pinion shaft 20 carries a pinion 21 at each end, each controlled by a clutch mechanism indicated at 22, and each driving one of the rear track sprockets 3 through a gear 23. The front track sprockets 2 are idlers. 60

In the rear of the track chains 4 is carried a transversely disposed pick-roll 24, Figs. 1, 2 and 4, adapted to dig into and loosen the salt, and to throw the same up and back onto the conveyer mechanism to be herein-after described. Said pick-roll 24 comprises 80 a hollow shaft 25, having a spindle 26 extending from each end and journalled at 27. A series of staggered diametrical holes are drilled in said hollow shaft 25, and through each of said holes is passed a double-ended pick 28, Fig. 4, having a notch 29 formed in one side and adapted to engage the wall of said hollow shaft 25. A wedge shaped key 30, driven in beside said pick 28, on the side opposite said notch, locks said pick 90 securely in position.

One of the pick-roll bearing spindles 26 carries a sprocket 31, Figs. 1 and 2, which is driven, through a chain 32, from a driving sprocket 33, Fig. 1, fixed upon the outer end of a transverse shaft 34, said transverse shaft being driven, in turn, through a pair of bevel gears 35 and a clutch 36 from a longitudinal shaft 37, which receives its 100

power from the main shaft 12 through spur gears 38.

The side members of the main tractor frame 1 are extended rearwardly, and support cross frame members 39, from which is suspended the conveyer frame 40, by means of adjustable rods 41, Figs. 2, 3, 4 and 5. Said rods 41 pass through tubular guides 42 secured in said cross frame members 39 and are threaded into hand wheels 43 by means of which said rods can be raised and lowered. Said rods 41 support longitudinal side members 44, to which the conveyer frame 40 is secured, and which are connected 15 with the tractor frame by longitudinal drag links 45, Figs. 1, 2 and 4. The bearings 27 of the pick roll 24 are also carried by said side members 44.

The conveyer frame 40 supports a transversely disposed trough whose center portion 46, Fig. 3, is horizontal and positioned immediately to the rear of the pick-roll 24, and whose end portions 47 slope upwardly and end in delivery chutes 48. The horizontal center portion 46 of said trough carries a forwardly extending foot 49, Fig. 4, adapted to dig through and under the salt loosened by the pick-roll 24, and to guide said loosened salt into said trough. A vertical shield 50, Figs. 3, 4 and 5, is provided at the rear of said trough to prevent the salt from passing through.

The salt, thus deposited in the horizontal portion 46 of said trough, is carried up one or the other inclined end portions 47 by a pair of endless chains 51, Figs. 1, 3, 4, and 5, having spaced drag flights 52 secured to and extending transversely between them. These chains are carried on idler sprockets 53, Figs. 3 and 5, and are driven, in either direction, by sprockets 54, Fig. 3, mounted on the rear end of a universally jointed shaft 55, Figs. 1 and 2, which receives its power through a reversing clutch 56, and a pair of spur gears 57, from the longitudinal side shaft 37.

In operation, the machine propels itself slowly over the bed of the salt-pond. The pick-roll 24, rotating considerably faster than the driving wheels, digs into and loosens up the salt, and throws the same up and back into the horizontal portion 46 of the conveyer trough. From there the salt is carried up either inclined end portion 47 of said trough, according to the direction of travel of the conveyer chains 51, and is dumped from one of the chutes 48 into any suitable receptacle or vehicle, not shown in the drawings.

The control mechanism may be arranged in any convenient manner, and is therefore not shown in detail in the drawings. The tractor is reversed by means of the bevel friction drive mechanism 13, Figs. 1 and 2; its speed is controlled by the selective

sliding gears 17 and by the speed of the engine 7; and it is steered by releasing the driving power from one track chain or the other by means of the clutches 22. The pick-roll 24 is started and stopped by the clutch 36. The conveyer mechanism is controlled by the reversing clutch 56, and the entire conveyer frame is adjusted by means of the elevating screw hand wheels 43 to operate at the proper depth in the salt bed.

Although we have herein described our machine as a salt-harvester, it is obvious that it may be used to loosen up, excavate and dispose of other material as well.

We claim:—

1. A harvester comprising a tractor; a pick-roll driven by the tractor and having teeth for penetrating, loosening and throwing a portion of the material to be harvested; a conveyer frame; a conveyer in said frame driven by the tractor for receiving and disposing of said material; an excavating foot carried by the conveyer frame, adapted to lift the remainder of the material loosened by the pick-roll and to deliver it to the conveyer; a frame carrying both the pick-roll and the conveyer frame; drag links connecting said carrying frame with the tractor; and means for adjustably suspending said carrying frame from the tractor to regulate the depth of cut of the pick-roll and the excavating foot.

2. A harvester comprising a tractor; a pick-roll driven by the tractor and having teeth for penetrating, loosening and throwing a portion of the material to be harvested; a conveyer frame; a conveyer in said frame driven by the tractor for receiving and disposing of said material; an excavating foot carried by the conveyer frame, adapted to lift the remainder of the material loosened by the pick-roll and to deliver it to the conveyer; a frame carrying both the pick-roll and the conveyer frame; drag links connecting said carrying frame with the tractor; and means for adjustably suspending said carrying frame from the tractor to regulate the depth of cut of the pick-roll and the excavating foot, said means consisting of screw rods fitted at their lower ends to the carrying, and at their upper ends to the tractor frame, and hand nuts on the upper ends of the screw-roads.

3. A harvester comprising a tractor; a pick-roll driven by the tractor and having teeth for penetrating, loosening and throwing a portion of the material to be harvested; a conveyer frame, having a horizontal lower portion and upwardly inclined sides, each terminating in a delivery end; a conveyer in said frame; means driven by the tractor for effecting the travel of the conveyer in either direction; and an excavating foot carried by the horizontal portion

- of the conveyer frame, adapted to lift the remainder of the material loosened by the pick-roll and to deliver it to the conveyer in said horizontal portion.
- 5 4. A harvesting machine comprising a tractor, vertically adjustable rods carried by the tractor, longitudinally extending bars connected to the rods, a shaft rotatably carried by the bars, teeth secured to the shaft, a conveyer, said conveyer comprising a horizontal center portion and upwardly extending inclined side portions supported by the longitudinally extending bars, and means for adjusting the rods for simultaneously raising or lowering the teeth-carrying shaft and conveyor.
- 10 5. A harvesting machine comprising a tractor including a frame having rearwardly extending portions, cross beams secured to the
- rearwardly extending portions, vertically adjustable rods extending through the cross beams, longitudinally extending bars connected to the rods, a shaft rotatably mounted on the bars, teeth secured to the shaft, a conveyor carried by the bars, means for adjusting the rods to simultaneously raise or lower the teeth-carrying shaft and conveyor, and drag links connecting the longitudinally extending bars to the tractor.
- 15 In testimony whereof we have signed our names to this specification in the presence of two subscribing witnesses.
